DESIGN FOR A LADY'S WRAPPER.

UNITED STATES PATENT OFFICE.

LIZZIE ROYS, OF NEW YORK, N. Y., ASSIGNOR TO THE BUTTERICK PUBLISHING COMPANY, (LIMITED,) OF SAME PLACE.

DESIGN FOR A LADY'S WRAPPER.

SPECIFICATION forming part of Design No. 18,295, dated May 1, 1868.

Application filed April 2, 1868. Serial No. 269,378. Term of patent 3½ years.

To all whom it may concern:

Be it known that I, LIZZIE ROYS, of the city, county, and State of New York, have invented and produced a new and original Design for a Pattern of a Lady's Wrapper; and I do hereby declare that the engraved prints accompanying this specification convey to any one accustomed to using paper patterns a clear understanding of how a garment made up by the pattern will appear.

The design shows full fronts depending from low-necked yoke portions and flaring over a high-necked vest that displays a box - plait down the center and fullness in the neck at either side of the plait; a close-fitting low-necked basque-back describing a point at its lower edge, and a full skirt depending from the point; a yoke portion extending from beneath the back to the neck and exhibiting a box-plait at its center; collar ornaments falling over from the low-necked fronts and back and in points back of the shoulders; a standing collar extending in a pointed strap at the left side, and slightly-flowing sleeves that display close-fitting sleeves extending from beneath their curved lower edges.

What I claim as my invention, and desire to secure by Letters Patent, is—

The design for a lady's wrapper, as shown in the engraved prints accompanying this specification.

LIZZIE ROYS.
